UNITED STATES PATENT OFFICE.

FELIKS BARNIAK, OF ROSEMONT, WEST VIRGINIA.

SHIP CONSTRUCTION.

1,309,875.

Specification of Letters Patent. Patented July 15, 1919.

Application filed January 17, 1919. Serial No. 271,734.

To all whom it may concern:

Be it known that I, FELIKS BARNIAK, a citizen of Poland, residing at Rosemont, in the county of Taylor and State of West Virginia, have invented certain new and useful Improvements in Ship Constructions, of which the following is a specification.

The primary object of the invention is the provision of a form of ship, whereby all 10 the passengers may be saved without leaving the ship even if the hull of the ship is damaged and sinks.

A further object of the invention is the provision of equilibrating means for ships, 15 which are out of the way when not in use but are readily and quickly positioned upon the water for maintaining the stability of the ship as well as maintaining the deck of the ship afloat upon the sinking of the hull 20 of the ship.

A still further object of the invention is to provide a safety means for sea-going vessels whereby the lives of the passengers will be more safe in the time of storm, a vessel 25 after the manner of my invention being capable of manufacture with only slight additional expense and without detracting from the appearance or the travel of the vessel, the structure being ready for instant use 30 whenever desired.

With these general objects in view the invention consists in the novel combination and arrangement of parts hereinafter fully described in connection with the accompanying 35 drawings in which like reference characters designate corresponding parts throughout the several views.

In the drawings,

Figure 1 is a side elevation of my im- 40 proved form of ship construction in its normal position,

Figs. 2 and 3 taken together show the invention in operation with the deck in floating position separated from the hull,

Fig. 4 is a top plan view of Fig. 2 with parts removed,

Fig. 5 is a vertical transverse sectional view taken upon line V—V of Fig. 1,

Fig. 6 is an end elevation of Fig. 2,

Fig. 7 is a vertical transverse sectional view taken upon line VII—VII of Fig. 3,

Fig. 8 is a side elevational view of a por-

tion of the hull upon a slightly enlarged scale,

Fig. 9 is a vertical transverse sectional 55 view upon line IX—IX of Fig. 8,

Fig. 10 illustrates a portion of the structure shown in Fig. 8, with the receiving pocket open,

Fig. 11 is a detail horizontal sectional 60 view of a portion of the deck illustrating the hull connecting means partially by dotted lines,

Figs. 12 and 13 are vertical sectional 65 views taken upon lines XII—XII and XIII—XIII respectively of Fig. 11, and

Fig. 14 is a vertical transverse sectional view through one of the floats and its retainer illustrated in Fig. 11.

Referring more in detail to the drawings, 70 the invention broadly consists of a ship having a hull 10 and a deck 11 detachably connected together, inflatable floats 12 being provided for supporting the deck 11 upon the water when the deck has been manually 75 separated from the hull and the hull 10 has sunk to the bottom of the sea by reason of some damage to the hull 10.

A plurality of pockets in the form of boxes 13 are provided in rows at the opposite sides of the hull 10 opening outwardly, each pocket having a suitable lid 14 normally maintains the same closed while a releasing cord 16 is provided for each latch extending upwardly through the side of the 85 hull 10 over an adjacent pulley 17 arranged therein and then wound upon a drum 18 centrally journaled longitudinally within the hull 10. By turning the drum 18 by any suitable means, the cords 16 are tightened 90 by winding upon the drum and the latches 15 released, permitting springs 19 with which the lids 14 are provided to automatically open the said lids to the positions best 95 illustrated in Figs. 2, 7 and 10 of the drawings.

One of the floats 12 heretofore mentioned is provided in each pocket 13 having an inflating tube 20 leading to a suitable point upon the deck 11 and attached to a pipe line 100 such as 21 provided upon the deck and supplied with air under pressure from a tank 22 having an air-compressor 23 also carried by the deck. The floats or balloons 12 may be

entirely or only partially deflated when stored away in the pockets 13 and it will be evident that upon releasing the latches 15 and simultaneously opening all of the lids 14, the floats 12 may be pulled out of the pockets 13 by means of the tubes 20.

- In the event of a storm or the requirement for further buoyancy for the ship, the floats 12 may be placed upon the water at the sides 10 of the hull 10, and inflated by means of the tank 22 and compressor 23 with either air or gas as may be found desirable. Any suitable connections are then employed for retaining the floats 12 in desired relations 15 to the hull 10, such for instance as cups 24 adjustably mounted upon the deck 11 by means of arms 25 slidably positioned through straps 26 upon the deck and retained adjusted by set screws 27.
- With the floats 12 inflated and positioned beneath the cups 24 at opposite sides of the ship as illustrated in Fig. 4 of the drawings, the floats will act as outriggers, preventing the ship from tipping and rendering the 25 same more seaworthy.

Means however are also provided for quickly disconnecting the deck 11 from the hull 10, whereby the deck may freely float away upon the sinking of the hull 10. A 30 releasable locking means is herein illustrated and is best noted in Figs. 11, 12, and 13 of the drawings consisting of bolts 28 slidably carried by the deck 11 and provided with hooks 29 adapted for detachable connection 35 with eyes or rings 30 mounted upon the upper part or roof 31 of the hull 10.

The bolts 28 are provided with toothed or rack portions 32 with which toothed segments 33 are in constant mesh, the said segments 40 being operable by levers 34 conveniently positioned upon the deck 11 such as within the cabin 35 carried by the deck.

In the event of imminent danger and probable shipwreck, the deck 11 may be detached from the hull 10 by shifting the levers 34 in the required direction to move the hooks 29 as desired for releasing the 45 hooks from the rings 30. With the floats 12 inflated, and positioned beneath the cups 24 or any other suitable means employed for 50 attaching the floats to the deck 11, the deck will be permitted to maintain itself afloat with the passengers positioned upon the deck and within the cabin 35 after the hull 55 10 has been demolished or has sunk beneath the water. When the floats 12 are within the closed pockets 13 very little obstruction is offered to the passage of the ship through the water while the device is ready for instant use whenever required.

A suitable wireless apparatus 36 is illustrated upon the deck 11 and also a pilot-room 37 at the forward end of the cabin 35. It will be understood that all of the super- 65 structure of the ship as the funnels 38 must

be attached to the deck 11 when the latter is detached from the hull 10. The detachable features of the deck 11 and hull 16 might also be employed without the use of the floats 12 if found desirable as the deck 70 is capable of floating but the floats 12 are advisable for increasing the buoyancy of the deck so as to carry a large number of passengers with safety in the event of an accident.

What I claim as new is:—

1. A ship construction comprising a hull, pockets in the sides of the hull opening outwardly thereof, closing lids for said pockets, opening springs for said lids, retaining latches for the latter, a removable deck upon said hull, releasing cords for said latches extending to points upon the deck whereby said latches are adapted for simultaneous automatic opening and floats removably positioned within said pockets and connected to the deck.

2. A ship construction comprising a hull, pockets in the sides of the hull opening outwardly thereof, closing lids for said pockets, opening springs for said lids, retaining latches for the latter, a removable deck upon said hull, releasing cords for said latches extending to points upon the deck whereby said latches are adapted for simultaneous 95 automatic opening, an inflatable float within each pocket, an inflating tube for each float extending to a source of air-supply upon the deck, the said floats being adapted for inflation when removed from the pockets and adjustable positioning means for the floats at the opposite sides of the deck.

3. A ship construction comprising a hull, pockets in the sides of the hull opening outwardly thereof, closing lids for said pockets, opening springs for said lids, retaining latches for the latter, a removable deck upon said hull, releasing cords for said latches extending to points upon the deck whereby said latches are adapted for simultaneous 105 automatic opening, floats removably positioned within said pockets and connected to the deck, rings carried by the hull, bolts 110 slidably carried by the deck having hook members removably positioned within said rings under normal conditions and operating means for said bolts whereby said hooks are released from the rings thereby disconnecting the deck from said hull at will.

4. A ship construction comprising a hull, pockets in the sides of the hull opening outwardly thereof, closing lids for said pockets, opening springs for said lids, retaining latches for the latter, a removable deck upon said hull, releasing cords for said latches 120 extending to points upon the deck whereby said latches are adapted for simultaneous automatic opening, an inflatable float within each pocket, an inflating tube for said float 125 extending to a source of air-supply upon the 130

deck, the said floats being adapted for inflation when removed from the pockets, adjustable positioning means for the floats at the opposite sides of the deck, rings carried by the hull, bolts slidably carried by the deck having hook members removably positioned within said rings under normal conditions

and operating means for said bolts whereby said hooks are released from the rings thereby disconnecting the deck from said hull at 10 will.

In testimony whereof I affix my signature.

FELIKS BARNIAK.
